UNITED STATES PATENT OFFICE.

WILLIAM W. WOLFE, OF EAST HIGHLANDS, CALIFORNIA.

DOOR-SPRING.

1,157,274.

Specification of Letters Patent.

Patented Oct. 19, 1915.

Application filed July 14, 1914. Serial No. 850,991.

To all whom it may concern:

Be it known that I, WILLIAM W. WOLFE, a citizen of the United States, residing at East Highlands, in the county of San Bernardino and State of California, have invented certain new and useful Improvements in Door-Springs, of which the following is a specification.

The object of this invention is to provide a spring adapted to close and hold closed a door, gate or like swinging closure hinged to swing in one direction, and the parts of which are so arranged that when the closure is swung to its full open position a resilient strength is exerted to hold the door in the open position.

A further object is to provide a device of this character in which an efficient closing action is obtained with the slightest opening of the door and the door will be normally held under tension in the closed relation.

With other objects in view, which will be referred to, my invention consists in the peculiar combination and novel arrangement of parts, such as will be hereinafter more fully described in connection with the accompanying drawing and more particularly pointed out in the appended claims.

In the drawing: Figure 1 is a view in side elevation showing my invention applied to a gate and with the gate closed. Fig. 2 is a top plan view of the disclosure in Fig. 1. Fig. 3 is a view in elevation of the gate in an open position and shows the relation of the parts in that connection.

The gate 1 is hinged at 2 to the gate post 3 in position to swing and close against the opposite gate post 4. A bell-crank plate 5 is pivoted at its angle at 6 to the body of gate 1. A stirrup 7 made curved as better shown in Fig. 2, is pivoted at its end as at 8 to the gate post 3, and a link 9 connects the loop of the stirrup 7 with one of the arms of the bell-crank plate 5. A coil spring 10 is secured at one end by a staple or other fastening means 11 adjacent the hinge side of the gate 1, and this spring 10 is connected at its free end by a link 12 with the free arm of the bell-crank plate 5.

When the parts are in the closed position as shown in Fig. 1, the spring 10 exerts the greatest tension to hold the gate in the closed position, as in this position the spring is working with the full leverage of the bell-crank plate around its pivot 6 to draw against the link 9 and the stirrup 7. As the

gate 1 is swung to its open position the bell-crank plate 5 is swung about its pivotal connection 6 by reason of the connection between the link 9 and stirrup 7 with the gate post 3, and this swinging of the plate 5 shortens the turning leverage of the connection of the links 12 with the plate 5 and at the same time lengthens the turning leverage of the connection of the link 9 with this plate. As the gate is brought to the full open position, the bell crank plate 5 is swung to the relation shown in Fig. 3 of the drawing, and the link 12 is carried to have its pivotal connection with the plate above the mounting 6 of the plate upon the door. With the parts in this relation, the point of connection of the link 9 with the plate 5 is disposed to exert the greatest possible leverage around the mounting 6, and the throwing of the link 12 to the position indicated lessens the leverage drawing action exerted by the spring and creates a drawing tension substantially against a dead center. With the parts in this relation, the door or closure when swung to an open position will be maintained in this open position until given movement in a closing direction.

If desired the links 9 and 12 could be so constructed that their length could be adjusted to procure different tension through the spring 10 and consequently vary in a measure the action of the door or gate in opening and closing, and it will be understood that other slight changes might be made in the form and arrangement of the parts without departing from the spirit and scope of my invention, and hence I do not wish to be limited to the disclosure except for such limitations as the claims may import.

I claim:

1. A door spring comprising a bell-crank plate mounted on the door with its turning axis at right angles to the central axis upon which the door swings, a stirrup connected with one of the arms of said bell-crank plate and pivoted to the door post, and a spring connected with the remaining arm of said plate and secured at its free end to the door.

2. A door spring comprising a bell-crank plate, a curved member pivotally mounted at its one end upon the door post and connected with said bell-crank plate in a manner that as the door is opened the plate is swung about its pivotal mounting, and a coil spring connected with the free arm of

said bell-crank plate and attached to the door to resiliently oppose swinging and to return the bell-crank plate to the normal position.

- 5 3. A door spring comprising a bell-crank plate mounted on the door, a link pivotally connected with one of the arms of said plate, a curved stirrup connected with said link and pivoted to the door post, a second link
- 10 connected with the remaining arm of the plate, a spring connected at its one end with the door and at its remaining end with said second link.
- 15 4. A door closing spring comprising a bell-crank plate, a pivot pin passed through the central bearing of said bell-crank plate to mount said plate upon the door with its

turning axis at right angles to the axis on which the door swings, a coil spring connected with one of the arms of said plate, a 20 connection between the free end of said spring and the door to hold said spring in tension, a curved member connected with the free arm of said bell-crank plate and a 25 pivotal connection between said curved member and the member to which the door is hinged.

In testimony whereof I affix my signature in presence of two witnesses.

WILLIAM W. WOLFE.
